UNITED STATES PATENT OFFICE

WILLIAM F. CASSEY, JR., OF MILBURN, NEW JERSEY, ASSIGNOR TO INTERNATIONAL COMMUNICATIONS LABORATORIES, INC., OF NEW YORK, N. Y., A CORPORATION OF NEW YORK

STEP-BY-STEP TRANSMITTER

Application filed March 7, 1931. Serial No. 520,857.

My invention relates to step-by-step transmitters and particularly to the type used in telegraphy and cable work wherein a perforated tape is used for carrying contacts to transmit the proper signals or message.

The transmitter mechanism is controlled by an intermittently operated electro-magnet and the mechanism is designed to cause the contacts to be closed for a maximum length of time to insure the positive transmission of signals.

This is accomplished by having the electro-magnet, on its energizing stroke and before its de-energization, withdraw the pecker rods which engage the perforator, advance the tape, and then permit the pecker rods to seek engagement with other perforations. No operation of the mechanism is dependent upon the return or de-energizing stroke of the electro-magnet.

Other features of my invention will be pointed out in the following description.

Referring to the drawing, I have illustrated the essential features of the mechanism embodying my invention.

The electro-magnet 1 is provided with an armature 2 attached to the arm 3 which is provided with the bearing or pivot 4.

The opposite end of the arm 3 is provided with a pawl 6 having a pivot or bearing 7.

The winding of the electro-magnet 1 is included in a circuit including a key 70, a rotating commutator or interrupter 71 and a source of current supply 72. When the key 70 is closed, the circuit through magnet 1 is completed and it is intermittently operated by the commutator 71.

The pawl 6 engages the teeth of the two ratchet wheels 10 and 20. The wheel 20 and the feed wheel 40 are mounted upon the shaft 42 and rotate therewith. The wheel 10 is loosely mounted upon shaft 42 but rotates freely upon it without causing the rotation of the shaft.

Associated with the wheel 10 is a cam wheel 30 also loosely mounted upon the shaft 42. The wheel 30 is, however, attached or coupled to the wheel 10 and rotates with it.

The periphery of the feed wheel 40 is pro-

vided with teeth 41 which engage perforations in the tape 80 to cause its advance.

The jockey arm 23, mounted loosely upon the shaft 37, is provided with a portion 25 which engages the teeth of the wheel 20. This jockey arm is provided with the pin 24 which engages the link 33.

This link is likewise loosely mounted upon the shaft 37 and is provided with a roller 34 having a bearing at 35.

This roller engages the raised portions 32 and the recessed portions 31 of the cam wheel 30. When the roller engages the raised portions, the arm 61, attached to the link 33 and 62, in turn engages the bell crank portions 45 and 55 which are mounted upon the bearing 60.

Attached to the arms 43 and 53 at 45 and 55, respectively, are the pecker rods 44 and 54.

The ends of these rods are arranged to engage perforations in the tape 80.

The ratchet wheel 20 is provided with more teeth than wheel 10; for instance, the wheel 20 is provided with twelve teeth and wheel 10 with nine. When the pawl 6 starts its movement, it first engages a tooth in wheel 10 and then engages a tooth in wheel 20.

The operation of the device is as follows:

The tape which is provided with two rows of perforations (in addition to those engaged by the feed wheel 40), which correspond to the code or message to be transmitted, is attached to the device.

The operator by closing switch 70 closes an intermittent circuit through magnet 1, which in turn intermittently attracts the armature 2 and operates the arm 3.

The operation of this arm upon the energizing stroke causes the pawl 6 to first engage a tooth in the wheel 10, causing it and the cam wheel 30 to start rotating.

The wheel 30, in moving, causes a raised portion 32 to engage roller 34, thus forcing down the arm 33, carrying the rod 61.

The rod 61 engaging the bell crank arms 43 and 53 causes the pecker rods to be drawn down from engagement with the tape or perforations in the tape.

As the pawl 6 further advances it engages a

tooth in wheel 20, causing the feed wheel 40 to rotate and advance the tape 80. The jockey arm 23 immediately starts downward with the movement of the tape and the pin 24 5 engages the link 33 and prevents it from rising. When the portion 25 of the arm 23 drops into the notch of the tooth of wheel 20, which will be when the feed of the tape is completed at one stroke, the pin 24 being 10 moved out of engagement with the link 33 allows it to move into a recess 31 of wheel 30. This action permits the pecker rods 44 and 54 to seek perforations in the tape.

It will be noted that all of the foregoing 15 functions are performed on the forward or energizing stroke of the electro-magnet 1.

Immediately after the de-energization of magnet 1 when its circuit is interrupted, the arm 3 and pawl 6 are restored under the influence of the tension spring 5.

In order to transmit impulses according to 20 the perforations in the tape engaged by the pecker rods 40 and 41, a set of controlling contacts are arranged to be operated by each 25 rod.

The lower end of the bell crank 43 is provided with a contact spring 46 and a co-operating contact 47, while the bell crank 53 is provided with a contact spring 56 and a co- 30 operating contact 57. When the pecker rods are not engaging perforations in the tape, the contacts which they control are separated, but when either pecker rod engages a perforation, its controlling contact is closed.

35 It has been explained how the pecker rods engage perforations on the forward or energizing stroke of the arm 3 controlled by the magnet 1. These rods remain in engagement and their respective controlling contacts remain closed after the de-energization of the magnet and until the next forward stroke. This insures a long contact time and produces signals or impulses of a maximum length.

While I have shown the pawl 6 intermittently operated by an electro-magnet, any other form of intermittent means for operation may be employed.

What is claimed is:

1. In a step-by-step transmitter, the combination of a perforated tape and a feed wheel therefor, a ratchet wheel and a cam wheel, an intermittently operated electro-magnet common to and for operating said ratchet and cam wheel, a pecker rod for engaging said tape, the operation of said cam wheel first causing said rod to disengage said tape, the operation of said ratchet wheel then causing the operation of said feed wheel to advance said tape and afterward to permit said rod to again engage perforations in said tape.

2. In a step-by-step transmitter, the combination of a tape and a pecker rod normally engaging said tape, an electro-magnet, means for energizing and de-energizing said

electro-magnet, and means controlled by said electro-magnet upon its energization and before its de-energization to cause said pecker rod to first disengage said tape, then to advance said tape and afterward permit the 70 pecker rod to again engage said tape.

3. In a step-by-step transmitter, the combination of a perforated tape and a feed wheel therefor, a cam wheel, an intermittently operated electro-magnet common to 75 and for causing the operation of both of said wheels, a pecker rod, for engaging perforations in said tape, the operation of said cam wheel causing said rod to first disengage a perforation in said tape, the operation of said feed wheel then causing said tape to advance and afterward permit the pecker rod to seek other perforations in said tape.

4. In a step-by-step transmitter, the combination of a perforated tape and a feed 80 wheel therefor, an intermittently operated electro-magnet for operating said wheel, a pecker rod for engaging the perforations in said tape, means controlled by said electro-magnet for first causing said pecker rod to disengage perforations in said tape the operation of said wheel then causing said tape to advance and after the completion of the advance permitting the pecker rod to seek other 85 perforations in said tape.

5. In a step-by-step transmitter, the combination of a perforated tape and an electro-magnet, means for energizing and de-energizing said electro-magnet, a pecker rod for engaging the perforations in said tape, means 100 controlled by said electro-magnet upon its energization and before its de-energization to first cause the pecker rod to disengage a perforation in said tape, then to operate said tape and afterward permit the pecker rod to 105 seek another perforation in said tape.

6. In a step-by-step transmitter, the combination of a perforated tape and an electro-magnet, means for energizing and de-energizing said electro-magnet, a pecker rod for engaging the perforations in said tape, means controlled by said electro-magnet upon its energization and before its de-energization to first cause the pecker rod to disengage a perforation in said tape, then to operate said 115 tape and afterward permit the pecker rod to seek another perforation in said tape, a set of contacts, and means controlled by said pecker rod to control said contacts depending upon its engagement with perforations in 120 said tape.

7. In a transmitter, the combination of a perforated tape and a pecker rod normally engaging a perforation therein, means for imparting intermittent movement to said tape, and means controlled by said intermittent means in a single movement to first cause said pecker rod to disengage the perforation in said tape, then impart a movement to said tape and afterward permit the 125 130

pecker rod to engage another perforation therein.

8. In a step-by-step transmitter, the combination of a perforated tape and an electro-magnet, a pecker rod for engaging the perforations in said tape, means for imparting an energizing and de-energizing movement to said electro-magnet, means controlled by said electro-magnet in one movement and before 10 its other movement to first cause the pecker rod to disengage a perforation in said tape, then to operate said tape and afterward permit the pecker rod to seek another perforation in said tape.

15 9. In a transmitter, the combination of an electro-magnet, means for energizing and de-energizing said electromagnet, a set of contacts, means controlled by said electromagnet first upon energization to open said contacts, 20 and additional means for then closing said contacts before de-energization of said electromagnet.

10. In a transmitter, the combination of an electromagnet, means for energizing and de-energizing said electromagnet, a set of contacts, means controlled by said electromagnet upon its energization to close said contacts, 25 and additional means to maintain said contacts closed until the next energization of said 30 electromagnet.

11. In a transmitter, the combination of an electromagnet, means for energizing and de-energizing said electromagnet, a set of contacts, means controlled by said electromagnet 35 upon its energization and before its de-energization to open said contacts, and additional means to close said contacts and to maintain them closed during said de-energization of said electromagnet.

40 12. In a transmitter, the combination of an electromagnet and an arm therefor, means for energizing and de-energizing said electromagnet to cause the movement of said arm, a set of contacts, means controlled by the arm 45 during its movement in one direction to open said contacts, and additional means to close said contacts and to maintain them closed during the movement of the arm in the opposite direction.

50 In witness whereof, I hereunto subscribe my name this 6th day of March 1931.

WILLIAM F. CASSEDY, JR.
